UNITED STATES PATENT OFFICE

WILLIAM ESTY, OF LACONIA, NEW HAMPSHIRE.

YARN-CARRIER FOR KNITTING-MACHINES.

SPECIFICATION forming part of Letters Patent No. 371,564, dated October 18, 1887.

Application filed March 10, 1887. Serial No. 230,386. (No model.)

To all whom it may concern:

Be it known that I, WILLIAM ESTY, of Laconia, in the county of Belknap and State of New Hampshire, have invented certain new and useful Improvements in Yarn-Carriers for Knitting-Machines, of which the following, taken in connection with the accompanying drawings, is a specification.

My invention relates to thread-carriers for knitting-machines; and it consists in a thread-carrier especially designed for delivering a yarn to each of two parallel rows of needles simultaneously, and for crossing the yarns from one row to the other at the opposite ends 15 of the rows, substantially in the manner in which the yarns are fed and crossed in the improved art or method of knitting presented in Letters Patent No. 302,119, granted to me July 15, 1884.

20 My invention further consists in the combination of a thread-carrier having a yarn-guiding eye at each end, a pinion on the shank or spindle of said yarn-guide, two rack-bars engaging with said pinion upon opposite sides 25 thereof, and a stop at each end of the traverse of said yarn-guide, constructed and arranged to be moved into line with either rack-bar, whereby the yarn-carrier may be rotated at both ends or one end only of its traverse, or it 30 may be traversed without rotating at either end of its movement when desired.

In the construction which I have now invented I provide an effectual lock for firmly holding the yarn-guiding eyes in the position 35 into which they are turned when they reach either end of the rows, but which shall at the same time readily yield to permit the turning movement of the said yarn-guiding eyes by which the yarns are crossed from the one row 40 of needles to the other, and vice versa. I also provide for lifting the said yarn guiding eyes as they are turned, to prevent them from engaging with the portions of the yarns or threads which extend from the eyes to the needles.

45 Figure 1 of the drawings is a plan of my improved yarn-carrier and parts connected therewith. Fig. 2 is an end elevation of the same parts. Fig. 3 is a sectional front elevation of the yarn carrier drawn to an enlarged scale. Fig. 50 4 is a vertical section on line $x-x$ on Fig. 3, and showing a portion of the central spindle with pinion-teeth cut therein in elevation. Fig. 5

is a horizontal section on line $y-y$ on Figs. 3 and 4. Fig. 6 is an elevation of the cams for raising and locking the yarn-carriers; and Fig. 55 7 is a central vertical section of a portion of the lower end of the spindle of the yarn carrier, said section being at right angles to the section shown in Fig. 4.

In the drawings $a-a$ are the yarn-guiding 60 eyes formed in the plates a' a'' , each provided with a shank, a^2 , which fits into an oblique hole formed one in each end of a short bar or plate, b , from the upper surface of which projects a pin, c , fitting in the slotted end of the 65 stem or spindle d and clamped therein by means of a collar, e , and set-screw f . The stem d passes through the block g , which is provided with the cylindrical projections h and i on the upper and lower sides thereof, re- 70 spectively. The upper projection, h , passes through an opening in the plate k , secured to or otherwise made part of the slide l , which is moved by any usual and well-known means from end to end of the slide-bar m , to deliver 75 the yarns to the needles, as customary. The upper projection, h , is screw-threaded at n , and after the said projection has been passed upward through the opening in plate k the closed cylindrical cap o is placed over the top 80 of the projection and screwed down upon the top of the plate k , thereby firmly securing the block g and parts carried thereby to the slide l . The upper end of projection h is cut away 85 on opposite sides, as shown at h' , so as to leave two projecting points, h'' , with inclined sides h''^2 . The stem d is also screw-threaded near its upper end, as shown at d' , and upon the same is placed a collar, d'' , interiorly threaded to fit the said threaded portion of the stem or 90 spindle. The screw-threads on said spindle are cut away on one side at d''^2 , and through the collar d'' is passed a screw, d''^3 , serving, when turned up against the flattened portion of the stem or spindle, to lock the collar 95 thereon. By turning the collar on the stem or spindle after loosening screw d''^3 the collar and its yarn-guiding eyes may be raised or lowered to any desired height. The lower end of collar d'' is cut away similarly to the 100 upper end of projection h , and so that the points on opposite sides of the collar will fit the notches of the projection, and vice versa. The spring p is placed upon the upper end of

the stem or spindle between collar d^2 and the closed end of the cap, and, pressing upon the collar, serves to depress the stem or spindle and maintain the points on the projection h and collar d^2 in the opposite recesses. A pinion, j , in the present instance formed of teeth, on the stem or spindle, is engaged by sliding rack-bars q , mounted on opposite sides of the same in ways formed therefor in the block g , which block constitutes the body of the thread-carrier, said bars being held to the block by the cap-pieces r . These bars are adapted to strike, as the carrier is moved toward either end of its traverse, against the stops s , mounted in bars t , which may be either fixed, or may be arranged to be slid backward or forward by hand or otherwise, to place the stops s at either end in line with either rack-bar, whereby the yarn-carrier may be rotated at one or both ends of its traverse, or it may be traversed without rotating at either end of its movement. By the contact of the rack-bars with the stops the stem or spindle d is turned so as to cross the yarns from one row of needles to the other. The stops may be adjusted in position or moved, as desired, to vary the action upon the rack-bars and stem or spindle, according as it is desired to have the work completely closed or open at one or both sides of the machine.

In my application Serial No. 249,335, filed September 10, 1887, I have shown pattern mechanism for determining the positions of these stops.

The opposed portions of the collar d^2 and projection h constitute cams, so that when the stem or spindle d is turned it is caused to move endwise or vertically as the inclined parts of the collar ride upon those of the projection. The effect of this is that as the spindle begins to turn to cross the yarns at the end of a course the yarn-guiding eyes are lifted to a higher level, thereby avoiding all danger of the yarn carrier as it turns from catching the portions of the yarns which extend from the eyes to the needles; also, by the fitting of the points on the projection h into the notches of the collar d^2 , and vice versa, an interlocking of parts is secured which prevents the yarn-guiding eyes from being disturbed from their proper positions, since the stem or spindle d cannot be turned until after sufficient power has been applied thereto to turn the collar upon the projection and overcome the power of the spring, which tends to hold the points of the collar in the lowest portions of the notches in the projection h .

In the present case the construction is such that the opposed cam-surfaces of the collar and projection h serve to not only lock the yarn-guiding eyes in adjusted position, but to raise the same as they are turned to cross the yarns. The said cam-surfaces, however, need be only of sufficient proportions to effect the locking of the stem and yarn-guiding eyes in

case it is not desired to lift the latter as they turn.

In another application of mine, filed September 10, 1887, and numbered serially 249,335, mechanism similar to that represented in this application is shown and described, but not claimed, except in combination with other devices not shown in the drawings of this case or described in this specification.

Having thus described my invention, what I claim as new, and desire to secure by Letters Patent of the United States, is—

1. The combination, with the stem or spindle d , the yarn-guiding eyes carried thereby, and the body of the carrier, of means for locking said stem and yarn-guiding eyes in adjusted position, consisting of a fixed projection on the body of the carrier, a collar on the stem or spindle, said projection and collar having corresponding interengaging points and recesses, and a spring for holding the collar pressed against the fixed projection, substantially as described.

2. The combination, with the stem or spindle d , the yarn-guiding eyes carried thereby, and the body of the carrier, of means for locking said stem and yarn-guiding eyes in adjusted position and raising the same momentarily during the turning thereof, consisting of a fixed projection on the body of the carrier, a collar on the stem or spindle, said projection and collar having corresponding engaging cam-surfaces, and a spring for holding the collar pressed against the fixed projection, substantially as described.

3. The combination, with the stem or spindle d , the yarn-guiding eyes carried thereby, and the body of the carrier, of the fixed projection h and collar d^2 , said projection and collar formed with the interengaging cam-surfaces, as described, the spring, and the cap, substantially as described.

4. The combination, with the stem or spindle d , having the pinion j , the yarn-guiding eyes carried thereby, and the body of the carrier, of the two rack-bars q , and a stop, s , at each end of the traverse of said yarn-guide, and constructed and arranged to be moved from the path of one rack-bar to the path of the other rack-bar, as may be desired.

5. The yarn-carrier plate b , provided with the pin c and an oblique hole in each end thereof, in combination with the plates $a' a'$, each provided with a shank, a^2 , and a yarn-guiding eye, a , and removably secured in one of the oblique holes in the plate b , as shown and described.

In testimony whereof I have signed my name to this specification, in the presence of two subscribing witnesses, on this 8th day of March, A. D., 1887.

WILLIAM ESTY.
